UNITED STATES PATENT OFFICE.

CLYDE FIFER, OF LANSING, MICHIGAN.

TRAFFIC SIGNAL.

Application filed December 19, 1923. Serial No. 681,586.

To all whom it may concern:

Be it known that I, CLYDE FIFER, a citizen of the United States, residing at Lansing, in the county of Ingham and State of Michigan, have invented certain new and useful Improvements in Traffic Signals, of which the following is a specification.

This invention relates to an improved traffic signal for motor vehicles and seeks, among other objects, to provide a simple and efficient device of this character which may be readily applied to motor vehicles of different makes and which may be easily operated for signaling an intention of the driver to turn or to stop.

The invention seeks, as a further object, to provide a signal embodying a single signal arm mounted to swing upwardly to horizontal signaling position and wherein, when the arm is swung upwardly, a circuit will be automatically closed through the signal lamp of the device for illuminating the lamp housing of the arms.

And the invention seeks, as a still further object, to provide a signal wherein as the signal arm is swung upwardly, the lamp housing will, in effect, be gradually enlarged so that beams of light of gradually increasing width will be projected from the housing to thus increase the effectiveness of the signal.

Other and incidental objects will appear hereinafter.

In the drawings:

Figure 1 is a rear elevation showing my signal applied.

Figure 2 is an enlarged detail sectional view on the line 2-2 of Figure 1, looking in the direction of the arrows.

Figure 3 is a longitudinal sectional view on the line 3-3 of Figure 2, looking in the direction of the arrows, and

Figure 4 is a detail sectional view on the line 4-4 of Figure 3, particularly showing the mounting of the lamp socket employed.

In carrying the invention into effect, I employ a housing 10 which may, as suggested in Figure 1, be screwed or otherwise secured to the side of a vehicle body, as conventionally illustrated at 11, and mounted to swing upon the housing is a signal arm 12. The housing as well as said arm may be formed of suitable sheet metal and, as brought out in Figure 3, the arm is hollow and is continued to form the upper section 13 of a lamp casing at

the outer end of the arm. Swingly mounted upon the section 13 of the casing is the lower section 14 of said casing, which latter section is formed to freely fit within the section 13 and is pivotally mounted thereon by a cross pin 15. Preferably, the lamp casing is rectangular in cross section and, as brought out in Figure 3, the sides of the section 13 are cut away to receive transparencies 16 secured near their forward ends by a clamp plate 17 and near their rear ends by lugs 18 extending from the side walls of the section. The transparencies 16 may be of celluloid and extending across said transparencies are dividing strips 20 integral with the side walls of the section and bent forward at their lower ends to form lugs 21 embracing the lower edges of the transparencies. The strips 20 are located near the forward end of the section and divide the transparencies into relatively small windows 22 at the forward end portion of the section and larger windows 23 at the rear end portion of the section, the windows 22 being preferably colored green and the windows 23 being preferably colored red. Likewise, the sides of the section 14 of the lamp casing are cut away to receive transparencies 24 secured by lugs 25 on said side walls. The transparencies 24 may also be of celluloid and are preferably colored red throughout. Further, the forward end portions of both of the sections 13 and 14 are cut away to receive transparencies 26 so that the casing sections are thus provided with windows at their outer ends.

At its inner end, the arm 12 extends into the housing 10 and pivotally connecting the arm with said housing is a cross pin 27. Engaged at its inner end with one side wall of the arm 12 near said pin is an eccentrically located rod 28 which extends forwardly through the arm 12 and is engaged at its forward end through one side wall of the section 14 of the lamp casing at a point near the cross pin 15, the rod being bowed upwardly at its outer end portion to clear the bottom wall of said section. Mounted upon the dash or other appropriate part of the vehicle is a sector 29 between the ends of which is arranged a bracket 30 and pivoted upon said bracket is a lever 31 mounting a latch 32 to operate with said sector. Extending from the latch through the outer end portion

of the lever is a rod 33 carrying a cap 34 and housed within the lever is a spring 35 holding the latch engaged with said sector. Attached to the lower end portion 5 of the lever is a rod 36 which extends freely through a suitable opening in the side wall of the vehicle body and at its outer end is pivotally connected with the arm 12 by a hinge 37 secured to the bottom wall of said 10 arm at its inner end. Thus, as will be seen, the lever 31 may be swung to the left, as seen in Figure 1, for swinging the signal arm upwardly when the latch will function to hold said arm in elevated position while, 15 by depressing the cap 34 to release the latch, the arm may be allowed to gravitate downwardly to its normal vertical position lying close to the side of the vehicle body.

Mounted upon one side wall of the housing 10 is an arcuate insulating block 38 mounting an arcuate contact plate 39 and secured to one side wall of the arm 12 is an insulating block 40 mounting a spring arm 41 upon the free end of which is journaled a roller 42 to cooperate with said plate, the arm being preferably covered by an insulating sleeve 43. Secured at its ends to the top wall of the section 13 of the lamp casing is a bracket 44 bent to form a sleeve 45 and mounted in said sleeve is a double-ended lamp socket 46. Removably engaged in the forward end of said socket is a lamp 47 and similarly engaged in the rear end of the socket is a plug 48 from which lead 35 circuit wires 49 and 50. As shown in Figure 3, the wire 49 is connected to the forward end of the spring arm 41 while the wire 50 is carried rearwardly through the arm 12 and through the housing 10 to provide an electrical ground return for the lamp. Leading from the battery or other suitable source of electrical energy upon the vehicle into the housing 10, is a feed wire 51 which is electrically connected with the contact plate 39. Thus, as will be seen, when the arm 12 is swung upwardly, as previously described, the roller 42 of the arm 41 will travel onto the contact plate 39 closing a circuit through the lamp 47 so that said 40 lamp will be energized for illuminating the lamp casing. On the contrary, when the arm 12 is permitted to swing downwardly to its normal position, the roller 42 will travel from the contact 39 onto the insulating block 38 so that the circuit through the signal lamp will be broken and the lamp extinguished. Thus, the signal lamp will be automatically energized and extinguished coincident with the swinging of the signal arm and, in this connection, it will, of course, be seen that the spring arm 41 will yieldably hold the roller 42 against the insulating block 38 as well as against the contact plate 39 so as to provide efficient electrical contact between the plate and roller.

Attention is now directed to the fact that as the arm 12 is swung upwardly, the rod 28 will function to swing the section 14 of the lamp casing of said arm upon the section 13 of said casing for gradually widening the effective area of the side and end windows of the casing so that as the arm continues in its upward movement, gradually widening beams of light will be seen at the front and rear of the casing while also, 75 a gradually widening beam of light will be seen at the outer end of the casing. Thus, the attention of traffic will be directed to the signal and the effectiveness thereof correspondingly enhanced. As will be appreciated, the section 14 of the lamp casing provides, in effect, a shutter to cooperate with the section 13 of said casing and it is further to be observed that as the arm 12 is swung upwardly, the windows 22 of the 80 section 14 will be uncovered by the red colored transparencies 24 of the section 14 so that a gradually widening green tinted beam of light will appear at each side of the lamp casing. Upon return of the arm 90 to its normal position, the section 14 of the casing will, of course, be coincidentally swung into the section 13 thereof to its normal position. The rod 28, therefore, provides a connection between the arm 12 and the section 14 of the lamp casing by means of which said section will be gradually swung coincident with the movement of said arm. In other words, the rod serves to swing the section in synchronized relation to the movement of the arm so that at no time can the section swing suddenly, but, on the contrary, the swinging movement of the section will gradually progress with the movement of the arm. It is true that since the lever 31 is manually operated, the speed of movement of said lever, incident to the practical operation of the signal, will vary, and in some instances the lever will, undoubtedly, be quickly operated to raise the 100 arm 12. However, even in such an instance, the individual movement of the section 14 will be distributed by the rod 28 over the full throw of the arm so that the swinging movement of said section will, in fact, be gradual as contrasted with an instantaneous movement of the section such as would occur by gravity in the absence of said rod. 110

Having thus described the invention, what is claimed as new is:

1. A traffic signal including a swingingly mounted signal arm having a constantly closed lamp casing, means for swinging said arm, and means coacting between the arm and casing for positively and gradually dilating the casing as the arm is swung.
2. A traffic signal including a swingingly mounted signal arm having a constantly closed lamp casing, means for illuminating said casing, means for swinging the arm,

and means coacting between the arm and casing for automatically and positively dilating the casing as the arm is swung whereby to release a gradually widening beam of 5 light from the casing.

3. A traffic signal including a swingingly mounted signal arm, a constantly closed lamp casing including a shutter, means for swinging the arm, means for illuminating 10 said casing, and means for gradually operating said shutter as the arm is swung for releasing light from the casing increasing as the arm is swung.

4. A traffic signal including a swingingly mounted signal arm, a lamp casing carried thereby and including a pivoted casing section, means for swinging the arm, means for gradually illuminating the casing, and means 15 for swinging said section coincident with the movement of the arm to release light from the casing increasing with the movement of the arm.

5. A traffic signal including a swingingly mounted signal arm, a sectional lamp casing

carried thereby, one of the sections being 25 stationary upon the arm and the other of said sections being pivoted upon the stationary section, means for swinging the arm, and a rod coacting between the arm and said pivoted section for rocking said section when 30 the arm is swung.

6. A traffic signal including a lamp casing comprising like pivotally connected sections normally nested one within the other, and means for positively and gradually swing- 35 ing one of the sections relative to the other.

7. A traffic signal including a lamp casing comprising companion channel-shaped casing sections having side walls and one fitting within the other, means extending 40 through the side walls of the sections pivotally connecting the sections near corresponding ends thereof, and means for positively and gradually swinging one of the sections relative to the other. 45

In testimony whereof I affix my signature.

CLYDE FIFER. [L.s.]
